US0D1035430S

(12) **United States Design Patent** (10) **Patent No.:** **US D1,035,430 S**
(45) **Date of Patent:** **** Jul. 16, 2024**

(54) **SHEET PILE CONNECTOR**

(71) Applicant: **Richard Heindl**, Gräfelfing (DE)

(72) Inventor: **Richard Heindl**, Gräfelfing (DE)

(**) Term: **15 Years**

(21) Appl. No.: **29/909,408**

(22) Filed: **Aug. 4, 2023**

(30) **Foreign Application Priority Data**

Feb. 6, 2023 (EM) 015010443-0009

(51) **LOC (14) Cl.** **08-08**

(52) **U.S. Cl.**

USPC **D8/382**

(58) **Field of Classification Search**

USPC D8/382, 394, 395; D25/119
CPC E02D 5/22; E02D 5/02; E02D 5/04; E02D
5/06; E02D 5/08; E02D 5/12; E02D
5/523; E02D 5/28

(57) **CLAIM**

The ornamental design for a sheet pile connector, as shown and described.

DESCRIPTION

FIG. 1 is a front perspective view of a sheet pile connector showing my new design; and,

FIG. 2 is a side view thereof.

The appearance of any portion of the article between the break lines shown in FIG. 1 forms no part of the claimed design.

1 Claim, 2 Drawing Sheets
